ABSTRACT OF THE DISCLOSURE

A flexible strap handle for detachable coupling to beaded rim containers. The handle is flexible and resilient and at each end of an elongated body member has a coupling portion for detachable coupling to the bead on the rim of containers such as food containers, paint cans, and the like. Each coupling portion has a hook section engaging the outside of the bead and a tongue section engaging the inside of the bead and the resiliency of the material and the shape thereof frictionally pinches the bead between the tongue section and the hook section thereby restraining the strap on the container during handling and other utilization thereof. The flexibility of the strap allows it to be deformed so it may be removed from the container to facilitate removal of the contents of the container.

BACKGROUND OF INVENTION

Field of invention

This invention relates to the handle art and more particularly to a flexible handle for detachable coupling to a beaded rim container.

Description of prior art

In many applications it is desirable to carry containers that have as their contents material that may cause direct handling of the containers uncomfortable. For example, many "take-home" restaurant type dispensing stores sell hot food in such containers for the patron thereof to take home and enjoy in the privacy of his own dwelling. These containers, as exemplified by, for example, those utilized at "Colonel Sanders' Southern Fried Chicken" establishments or "Chicken Delight" establishments are often made of cardboard or plastic coated cardboard or similar materials having a beaded or rolled rim around the upper edge portions thereof. A lid or other closure member is often provided with these containers and is set below the beaded rim a predetermined distance on the order of one-half an inch to one inch, more or less.

To the best of applicant's knowledge there has not, heretofore, been available a handle for conveniently handling or carrying such containers. Further, in the storing and shipping of these containers prior to their utilization, they are often stored nested and to minimize storage and shipping costs the nesting is as compact as possible. Therefore, the handle for such containers should, preferably, be detachable from the container and be able to be stored and shipped as a separate item. Further, such handles since they are often utilized in throw away or disposable type application, should preferably be economical to manufacture and utilize.

It will be appreciated that while applicant's invention is described herein as utilized in an embodiment for a detachable handle for a food container, applicant's improved strap handle may equally well be utilized on any container, such as paint buckets, or the like, wherever there is a construction of the container providing the equivalent to a beaded rim.

2**SUMMARY**

Accordingly, it is an object of applicant's invention herein to provide an improved handle arrangement.

It is another object of applicant's invention herein to provide a handle arrangement for beaded rim containers.

It is another object of applicant's invention herein to provide an improved handle for detachable coupling to beaded rim containers.

The above and other objects of applicant's invention are achieved, according to one embodiment of applicant's invention, by providing an elongated flexible resilient body member comprising applicant's improved strap handle. The body member has a central portion which is adapted to be gripped when transporting the container upon which the improved strap handle is utilized. At each end of the central portion there is a coupling portion that is adapted to be detachably coupled to the bead of such a beaded rim container. The coupling portion comprises a hook section that engages the outside surface of the bead and a tongue section that engages the inside surface of the bead. The flexible resiliency of the strap handle provides a pinching action between the tongue and the hook section so that the beaded rim is pinched therebetween.

Applicant has found that forces exerted on the strap handle as experienced during carrying a container by means of the strap handle tend to increase the frictional pinching between the tongue member and the hook member to provide a tighter grip of the strap handle on the container. The strap handle is basically a flat member with only slight projections at the coupling portion and consequently may be conveniently stored and shipped. The flexible resiliency of the strap handle allows the strap handle to be restorably deformed so that it may be detachably coupled to the beaded rim.

Brief description of drawing

The above and other embodiments of applicant's invention are explained in detail in the following detailed description taken together with the accompanying drawing wherein similar reference characters refer to similar elements throughout and in which:

FIGURES 1 and 2 illustrate one embodiment of applicant's invention as utilized on a beaded rim container;

FIGURES 3 and 4 illustrate the embodiment of applicant's invention shown in FIGURES 1 and 2;

FIGURES 5 and 6 illustrate another embodiment of applicant's invention; and

FIGURES 7, 8 and 9 illustrate another embodiment of applicant's invention.

Description of preferred embodiments

Referring now to FIGURES 1, 2, 3 and 4 of the drawing, there is shown one embodiment of applicant's invention, generally designated 10 as utilized, for example, on a beaded rim container 12. The beaded rim container 12 has a rolled or beaded rim 14 along the upper edge thereof and the bead 14 along the upper edge thereof and the bead 14 has an outside portion 16 on the external side of the container 12 and an inside portion 18 on the internal side thereof. The container 12 may often be provided with a lid 20 that fits detachably into a groove 22 on the internal wall of the container 12 and is spaced a preselected distance below the bead 14. The lid 20 snaps into place in the groove 22 to provide a sealed volume 24 for the storage of, for example, fried chicken or any other commodity as may be desired.

This description of a beaded rim container is presented so that the operation and utilization of applicant's improved strap handle may be better understood. It will be

appreciated, of course, that the container *per se* does not form a part of applicant's invention herein.

The embodiment of applicant's invention **10** shown in FIGURES 1 and 2 and as shown in greater detail in FIGURES 3 and 4 comprise an elongated flexible resilient body member **26** having a central portion **28** that, when utilized as indicated in FIGURES 1 and 2, is adapted to be gripped by the hand so that the container **12** may be supported from the strap handle **10**.

The strap handle **10** further has a pair of coupling portions **30** and **32** at each end of the central portion **28** and the coupling portions are adapted to be detachably coupled to the bead **14** of the container **12**. The coupling portions **30** and **32** are identical and are comprised of a hook section **34** and a tongue section **36**. The hook section **34** is adapted to engage the outside surface **16** of the bead **14** and the tongue section **36** is adapted to engage the inside of the bead **14** and the resiliency of the strap **10** pinches the bead **14** between a tongue section **36** and the hook section **34**.

The tongue section **36** is spaced apart from the hook section **34** and is resiliently hinged to the central portion **28**.

In order to detachably couple and uncouple the strap handle **10** from the container **12**, the strap handle may be resiliently and restorably deformed by placing the end **38** of the hook section **34** against the bead and bending the central portion **28** in a direction indicated by the arrow **40**. Such motion moves the tongue section **36** sufficiently away from the hook section **34** so that it may fit over the inside of the bead **14**. Leaving the handle **10** to return to its position before moving in the direction of the arrow **40** provides the resilient gripping action for the frictional pinching of the bead **14** between the tongue section **36** and the hook section **34**. In addition, it will be appreciated, that the tongue section **36** may, by itself, be otherwise spread apart from its relationship to the hook section **34** as indicated in FIGURES 3 and 4 by any desired means in order that it may be detachably secured to the beaded rim **14** as indicated in FIGURES 1 and 2.

In the embodiment shown in FIGURES 1, 2, 3 and 4, the coupling portions **30** and **32** further comprise a pair of arms **42** and **44** in spaced apart relationship that connect a gripping portion **46** to the central portion **28**. In this embodiment the tongue section **36** is positioned between the arms **42** and **44** and is an extension of the central portion **28**.

The flexible resilient nature of applicant's improved strap handle **10** may be provided by fabricating the strap handle **10** from any desired flexible resilient material such as linear polyethylene, polypropylene, or similar such plastic or other materials. When fabricated from such plastics as above-mentioned, it may be injection molded, formed and die cut, or stamped, or the like.

It can be seen from FIGURES 1 and 2 that applicant's improved strap handle **10** conveniently fits on the container **12** even though the lid **20** thereof is in place and thus allows convenient transportation of the container **12** when desired.

It will be appreciated that applicant's invention may be made in various forms. FIGURES 5 and 6 illustrate another arrangement of applicant's invention wherein there is provided a strap handle designated **50** having a central portion **52** and a coupling portion **54** coupled to one end thereof and a similar coupling portion (not shown) coupled to the other end thereof. The coupling portion **54**, in this embodiment of applicant's invention, is comprised of a hook section **56** and a tongue section **58**. However, as shown in FIGURES 5 and 6 the hook section **56** is comprised of a first straight segment **60** angled from the plane defined by the central portion **52** and a second straight segment **62** at an acute angle to the first section **60** and spaced from the central portion **52**.

The tongue **58**, in this embodiment of applicant's invention, is also positioned between a pair of arms **64** and **66** that couple the hook section **56** to the central section

5 **52**. The operation of this embodiment of applicant's invention is similar to that described above in the embodiments shown in FIGURES 1, 2, 3 and 4, in providing a detachable coupling to a beaded rim container (not shown). That is, the first straight segment **60** may be resiliently spread apart from the second straight segment **62** and the tongue section **58** may similarly be resiliently spread apart from its relationship to the hook section **56** so that a bead or other upper rim projection as may be provided on a container may be slipped therebetween for frictional pinching and retention.

10 **15** In the embodiment shown on FIGURES 3 and 4, it can be seen that both the arm portions **42** and **44**, as well as the gripping portion **46**, are curved and are out of the plane defined by the central portion **28**. Thus, while the preferred embodiments of applicant's invention shown herein indicate that the coupling portions do not lie in the same plane as the central portion of applicant's improved strap handle, it will be appreciated that variations **20** in this construction in which the tongue section **58**, the hook section **56** or portions thereof, may be substantially coplanar with the central portion of the strap handle.

25 FIGURES 7, 8 and 9 illustrate another embodiment of applicant's invention of an improved detachable strap handle. In many applications of applicant's invention, applicant has found that there may be a tendency of certain combinations of strap handle material and container material to allow laterally directed movement of the strap handle on the beaded rim of the container. That is, as shown on FIGURE 1, the strap handle could, in certain applications, rotate on the beaded rim around the periphery thereof. In order to prevent such lateral movement and to provide a better frictional retention between the rim and the coupling portion of the strap handle, applicant has provided the arrangement illustrated in FIGURES **30** 7, 8 and 9.

35 As shown thereon, this embodiment of applicant's invention, generally designated **70**, is provided with an elongated flexible resilient body member **72** comprising the strap handle and having a central portion **74** and a coupling portion **76**. In this embodiment of applicant's invention the central portion **74** may be provided with a flat section **75** which is gripped in the hand during transporting of the container to which the strap handle may be attached and an intermediate section **77** between the flattened section **75** and the coupling portion **76**. The intermediate section **77** may be of any desired cross-sectional shape and preferably has substantially equal bending characteristics in any direction.

40 **45** The coupling portion **76** is provided with a hook section **78** and a tongue section **80**. As with the other embodiments of applicant's invention described above, the tongue section **80** is resiliently hinged to a flattened section **81** of the coupling portion **76** and is spaced apart from the hook section **78**.

50 **55** The hook section **78** is provided with a pair of arms **82** and **84** for supporting gripping section **86** in opposed relationship to the tongue section **80**. In this embodiment of applicant's invention, the arms **82** and **84** extend part of the way around the hook section **78** from the flattened section **81**. The gripping section **86** is provided with a comparatively sharpened edge **88** opposite the tongue section **80** to provide better gripping between the side of the container and the beaded rim portion. That is, the sharpened edge **88** tends to dig into and more securely retain the handle on the container.

60 **65** **70** **75** To prevent lateral movement of the improved strap handle **70**, applicant provides a pair of tab members **90** and **92** that, when the strap handle **70** is positioned on a container such as the container **12** of FIGURE 1, the forward edges **94** and **96** thereof, respectively, engage the external surfaces of the rim and thus provide a greater percentage of the total circular periphery of the beaded rim, as shown for example in FIGURE 2, in contact with at least a portion of the strap handle **70**. This engage-

ment of the tabs 90 and 92 with the beaded rim tends to prevent the above mentioned lateral movement around the rim.

When the container 12, of FIGURES 1 and 2, is fabricated from a comparatively soft material, such as cardboard or the like, or in other applications, applicant also prefers to provide a pair of V-shaped ridges 98 and 100 on the undersurface 102 of each of the pair of arms 82 and 84. As can be seen, the V ridges 98 and 100 extend around the hook section 78 to the gripping portions 86 and may, if desired, extend around the gripping portion 86 also. When the strap handle 70 is positioned on a beaded rim container, the V-shaped ridged 98 and 100 tend to dig into the beaded rim to provide a better gripping action therebetween and thus also help prevent lateral movement of the handle on the beaded container and provide a better retention therebetween.

Further, the slot 104 in the edge 88 of the gripping section 86 provides additional corners 106 and 108 to provide gripping action against the underside of the beaded rim in the case of misalignment or the like.

Thus, the embodiment of applicant's invention illustrated in FIGURES 7, 8 and 9 provide a firmer and more secure grip on the beaded rim of such a container.

This concludes the description of applicant's invention of an improved strap handle. From the above it can be seen that applicant has provided an improved flexible strap handle that may be conveniently detachably coupled to beaded rim containers so that the containers may be supported by and carried by the strap handle. The strap handle may be economically fabricated so that it may be utilized in disposable applications. Further, the strap handle of applicant's invention may be conveniently stored in a substantially flat condition, thereby minimizing storage and shipping costs.

Those skilled in the art may find many variations and adaptations of applicant's improved invention. Therefore, the following claims are intended to cover all such variations and adaptations falling within the true scope and spirit of applicant's invention.

What is claimed as new and desired to be secured by Letters Patent of the United States is:

1. A strap handle for beaded rim containers comprising, in combination:

an elongated, flexible, resilient body member having a central portion and a pair of coupling portions, one of said pair of coupling portions disposed on each end of said central portion;

each of said coupling portions for detachable coupling to the bead of the beaded rim container and comprising a hook section for engaging one side of the beaded rim at a predetermined location thereon, and a tongue section adjacent to and spaced apart from said hook section and resiliently hinged to said central portion for engaging an opposite side of the bead at said preselected location for detachably, frictionally pinching the bead between said hook section

and said tongue section to restrain said bead therebetween; and

said hook section comprises a gripping portion and a pair of spaced apart arm portions connecting said grip portion to said central portions; and
said tongue section is positioned between said arm portions.

2. The arrangement defined in claim 1 wherein: said arm portions and said gripping portions comprise straight segments.

3. The arrangement defined in claim 1 wherein: said arm portions and said gripping portions are curved, and said gripping portion engages the outside of said bead and said tongue section engages the inside of the bead.

4. The arrangement defined in claim 1 wherein: said hook section further comprises a pair of side tabs in spaced apart relationship coupled to said spaced apart arm portions and having bead engaging edges spaced apart from said gripping section of said hook section; and
said gripping section is further provided with a sharpened edge for engaging the intersection between the beaded rim and the wall of the container.

5. The arrangement defined in claim 4 and further comprising:

a pair of T-shaped ridges extending along the underside of said spaced apart arm portions for engaging the beaded rim of the container along the edge of said V-shaped ridges.

6. The arrangement defined in claim 5, wherein: said sharpened edge of said gripping section is provided with a notch therein positioned substantially opposite said tongue section.

7. The arrangement defined in claim 1, and further comprising:

a pair of V-shaped ridges, one of said pair coupled to each of said pair of spaced apart arm portions on the under surface thereof, extending along said under surface of said arm portions toward said gripping section for engagement with the beaded rim of the container, whereby the edges of said V-shaped ridges dig into the beaded rim of the container to prevent movement of the strap handle on the beaded rim.
